(57) **CLAIM**

The ornamental design for an automatic dunnage bag inflator, as shown and described.

DESCRIPTION

FIG. 1 is a front perspective view of an automatic dunnage bag inflator, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof;

FIG. 7 is a right-side elevational view thereof; and,

FIG. 8 is a rear perspective view thereof.

The broken lines in FIG. 8, attached to the bottom of the automatic dunnage bag inflator illustrate environment. All other broken lines in the figures show portions of the automatic dunnage bag inflator. None of the broken lines form any part of the claimed design.
